UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

OIL-BURNING ENGINE.

Application filed December 2, 1924. Serial No. 753,503.

To all whom it may concern:

Be it known that I, BENJAMIN C. SMITH, a citizen of the United States of America, residing at Bayonne, New Jersey, have invented a new and useful Oil-Burning Engine, of which the following is a specification.

My invention relates to certain new and useful improvements in engines of the so-called Diesel type and comprising a plurality of cylinders operating on a single crank shaft.

The main object of the present invention is to provide a simple and effective means for adjusting and controlling the time of operation of the fuel feed valves.

In the drawings—

Fig. 1 is a side elevation of an engine constructed to embody my invention, certain parts being omitted and other portions being broken away.

Fig. 2 is a relatively enlarged cross sectional view of a cylinder looking down on certain parts shown in elevation, this view being taken on the line 2—2 of Fig. 1.

Fig. 3 is a relatively enlarged longitudinal section of part of the adjusting and controlling mechanism;

Fig. 4 is an end view, partly in section, of one of the cylinders and associated parts, certain portions being broken away.

1 represents the engine base. 2 is one of the cylinders. 3 is a fuel feed valve mounted in the upper part of the cylinder 2 and through which fuel is forced at the proper time. 4 represents a cam shaft driven in the usual way from the engine shaft (not shown). 5 is a rocker arm mounted on a suitable shaft support 6. One end of this arm engages the cam shaft, the other end passing through a slotted pivot stud 7 at the lower end of a draw-rod 8, which is connected at its upper end to a rocker 9, pivoted at 10 and having a fork 11 suitably engaging the stem 12 of the fuel inlet valve, so that the latter will be opened at the proper time by the operation of a cam on the cam shaft 4. The particular mechanical construction of these various parts, as well as the mechanical construction of the fuel feed valve is non-essential.

My invention relates more particularly to the means by which the operation of the fuel feed valve may be controlled, and this is shown more in detail in the sectional

view, Fig. 3. It will be observed that the lower end of the draw-rod 8 is mounted in a sleeve 13, which latter is threaded on its outer side toward the lower end and makes threaded engagement with a surrounding sleeve 14 which sleeves may be regarded as a part of the draw-rod. The sleeve 14 carries the slotted stud 7 and slides in a bushing 15 in the base 1 of the engine. The lower end of the rod 8 proper is provided with a head 8^a, which is held normally against the under side of the sleeve 13 by the tension of the spring 16 or by any other suitable means.

It is obvious that if means are provided to turn the sleeve 13 relatively to the sleeve 14, the former will move longitudinally relatively thereto in one direction or the other, and it is by thus shifting the relative angular position of these two sleeves 13 and 14 that the over all operative length of the draw-rod may be changed so as to produce a corresponding change in the length of time that the fuel feed valve will be held open. To provide means for rotating the sleeve 13 relatively to the sleeve 14 while the engine is running I preferably employ a construction as shown in the drawings, comprising an arm 17 secured to the upper end of the sleeve 13, and another arm 18, which is secured on said sleeve 13. 20 is a stud bolt mounted on the arm 18, and 21 is a gear mounted to turn on the stud bolt 20. 22 is a thumb piece on the gear 21 for rotating the same when the nut 23 on bolt 20 is freed. The outer edge of the arm 17 is formed as a segment, and the gear 21 meshes therewith. By loosening the nut 23 the gear 21 may be rotated so as to shift the angular position of the arm 18 relatively to the arm 17, thereby varying the fixed adjustment of the sleeves 13—14. When the desired adjustment has been made the nut 23 may be screwed down to lock the gear 21, whereupon the arm 18 will have a fixed angular position relatively to the sleeve 13.

24 is a link which is secured to the outer end of the arm 18, and this link 24 may be connected with an operating lever 25, which may be associated with a segment 26 so that, by swinging the lever 25 to and fro, the arm 18 may be swung to and fro, thereby turning the sleeve 13 in the sleeve 14 and lengthening or shortening the operative over all length of the draw-rod 8, and thereby vari-

ably controlling the operation of the fuel feed valve 3. Each cylinder may be provided with a corresponding means in connection with the draw-rod thereon for the 5 fuel feed valve, and in order that the fuel feed valves in the several cylinders may be controlled in unison these controlling parts may be connected by links, one of which is indicated at 27.

10 I claim:

1. In an engine of the character described, a fuel feed valve for each cylinder unit, a cam shaft, a connection between the cam shaft and said valve, including a rod, 15 a rocker actuated by the cam shaft and in turn actuating the rod, and means for varying the effective length of said rod while the engine is in motion to vary the operation of said fuel feed valve, said means including a non-rotatable sleeve extension on said rod and a relatively rotatable sleeve extension on said rod, a screw thread connection between said sleeves, and means for turning one of said sleeves relatively to the 20 other, for the aforesaid purpose.

2. In an engine of the character described, a fuel feed valve for each cylinder unit, a cam shaft, a connection between the cam shaft and said valve, including a rod, 30 a rocker actuated by the cam shaft and in turn actuating the rod, and means for varying the effective length of said rod while the engine is in motion to vary the operation of said fuel feed valve, said means including a non-rotatable sleeve extension on said rod and a relatively rotatable sleeve extension on said rod, a screw thread connection between said sleeves, and means for turning one of said sleeves relatively to the 35 other, for the aforesaid purpose, comprising an arm projecting laterally therefrom and a manually operable link connected to said arm.

3. In an engine of the character described, a fuel feed valve for each cylinder unit, a cam shaft, a connection between the cam shaft and said valve, including a rod, 45 a rocker actuated by the cam shaft and in

turn actuating the rod, and means for varying the effective length of said rod while 50 the engine is in motion to vary the operation of said fuel feed valve, said means including a non-rotatable sleeve extension on said rod and a relatively rotatable sleeve extension on said rod, a screw thread connection between said sleeves, and means for turning one of said sleeves relatively to the other, for the aforesaid purpose, comprising an arm projecting laterally therefrom and a manually operable link connected to 55 said arm, a second arm carried by the same sleeve and adjustable with respect to the first arm and located between the first arm and said link.

4. In a multi-cylinder engine of the character described, valves for each cylinder unit including a fuel feed valve, a cam shaft for operating all of said valves, connections between said cam shaft and the fuel feed valves in each unit, each connection comprising a rocker arm actuated by the cam shaft, and an extensible rod engaged by said rocker arm, and means whereby the effective length of all of said rods may be simultaneously increased or diminished 75 while the engine is running.

5. In a multi-cylinder engine of the character described, valves for each cylinder unit including a fuel feed valve, a cam shaft for operating all of said valves, connections 80 between said cam shaft and the fuel feed valves in each unit, each connection comprising a rocker arm actuated by the cam shaft, and an extensible rod engaged by said rocker arm, and means whereby the effective length of all of said rods may be simultaneously increased or diminished 85 while the engine is running, said means including a sleeve extension on each rod and a sleeve extension on each first-mentioned sleeve, 90 screw thread connections between each set of sleeves, one of the sleeves in each set being rotatable relatively to the other, for the aforesaid purpose.

BENJAMIN C. SMITH.
